UNITED STATES PATENT OFFICE.

SAMUEL KOFF, OF BROOKLYN, NEW YORK.

FOLDING BOX.

Application filed February 11, 1925. Serial No. 8,458.

To all whom it may concern:

Be it known that I, SAMUEL KOFF, a citizen of United States, residing at Brooklyn, in the county of Kings and State of New York, have invented certain new and useful Improvements in Folding Boxes, of which the following is a specification, reference being had therein to the accompanying drawing.

10 The present invention relates to folding paper or card-board boxes, and aims to provide a folding box of novel construction having double thicknesses at the corners between the walls and also having fold lines enabling the box to be readily and compactly folded.

Another object of the invention is the provision of a folding box having simple and inexpensive means for holding the box in shape when unfolded, so as to prevent the box collapsing or folding by itself, and enabling the opened or unfolded box to be conveniently handled and filled.

Another object of the invention is the provision of a folding box having flaps to overlie the contents of the box and adapted to be folded with the box into flat form.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a perspective view of the box in open or unfolded position, a portion being broken away.

Fig. 2 is a plan view of the box partially folded.

Fig. 3 is a plan view of the box when completely folded.

Fig. 4 is a plan view of the blank from which the box is made.

Fig. 5 is a perspective view of the box having closure flaps.

Fig. 6 is a cross section of the box shown in Fig. 5 with the flaps in closed position.

Fig. 7 is a plan view showing the box folded, portions being broken away.

Fig. 8 is a perspective view of another form of box with closure flaps, portions being broken away.

Fig. 9 is a plan view of the box of Fig. 8 folded flat, portions being broken away.

The box shown in Figs. 1, 2 and 3 is rectangular in shape, although it may be square, and may be made in different sizes, 60 being composed of a single blank (Fig. 4) of suitable paper or card-board. The box has a bottom 14, side walls 15 and end walls 16. Said side and end walls have the respective flaps 17 and 18 of triangular shape, 65 which in the blank, which is rectangular without cut-outs or waste of material, occupy the corner portions of the blank between the end and side walls, the only slitting of the blank being from the four corners of the blank to the corners of the bottom 14. There are fold lines 20 between the bottom and side walls; fold lines 21 between the bottom and end walls, and fold lines 22 between the walls and flaps. In addition, 70 the end walls 16 have diagonal fold lines 23 extending from the corners of the bottom to the upper edge of the end walls. Said fold lines 20, 21, 22 and 23 are all provided in the blank, before completing the box, by scoring 75 or creasing the blank to facilitate bending of the material along the fold lines.

The side and end walls are bent upwardly, and the flaps 17 are bent at an angle to the walls to which they are attached. The flaps 80 18 overlap the side walls 15 at the inner surfaces thereof, while the flaps 17 overlap the end walls at the outer surfaces thereof, said flaps being secured to the walls by means of staples 19 or other securing elements. 85 The box thus has double thicknesses at the corners between the walls, for purpose of strength.

The diagonal or hypotenuse edges of the flaps 17 coincide with the fold lines 23 of the end walls, in order that the box may be conveniently folded into flat form. Thus, as seen in Figs. 2 and 3, the box is folded by swinging the end walls 16 outwardly and the side walls 15 inwardly, the end walls 16 folding on the lines 23. When the blank is folded, the side walls 15 bear on the bottom 14, with the middle portions of the end walls 16 in the same plane as the bottom, and the flaps 17 and corresponding portions of the end walls are folded flat with the side walls. This enables the folded boxes to be stacked conveniently and compactly.

By having the fold lines 23 coinciding with the corresponding edges of the flaps 17, 110

the end walls are strengthened by said flaps when the box is unfolded, and the fold lines 23 would produce weaker portions of the box were it not for the fact that said fold 5 lines extend along the corresponding edges of the flaps 17.

In order to overcome the tendency for the box to collapse or fold when it is opened, due to the presence of the fold lines 23, 10 strips 24 or other suitable bendable means are employed. Said strips are of pliable metal or material which may be readily bent by hand, and which will retain its shape against the tendency of the box to spring 15 out of shape. These strips 24 are readily positioned between the side and end walls and the flaps 18 and 17, respectively, when preparing the box for stapling, and when the staples 19 or other securing means are 20 applied, said strips will be held firmly in and permanently secured to the double corner portions of the box, with said strips extending across the folds or bends 22. Such strips are concealed, so as to be out of sight, 25 and it is only necessary to use one of the strips at each end of the box. When folding the box, said strips 24 will be flattened out, and being bent straight will have a tendency to hold the box in its folded position. When 30 the box is unfolded, the end walls 16 being swung upwardly, and preferably moved slightly between the side walls, will bend the strips 24 at right angles, and this will support the end walls 16 in upright positions. 35 The box is therefore retained or maintained in open position, when unfolded, so that it may be conveniently handled and filled, without the liability of the box collapsing or folding.

40 Figs. 5, 6 and 7 show a box of similar construction, with the side walls 15 provided with flaps 25 at their upper edges to swing inwardly over the contents of the box when it is filled, and said flaps 25 may be of sufficient width to overlap one another as seen in Fig. 6. The flaps 25 have props 26 at their ends to be disposed at the inner surfaces of the end walls 16, and to seat on the bottom 14, in order to prevent the flaps 25 45 from being pressed down. This is particularly desirable when a cover is used to fit over the box, as disclosed in my copending application Serial No. 627,346, filed March 24, 1923.

50 A modification is shown in that the bendable strips 24' are positioned on the outer surfaces of the end walls 16 with their terminals secured behind the flaps 17, said strips extending across the fold lines 23. 55 The strips 24' are bent, as seen in Fig. 7, when the box is folded, and are straightened out when the box is unfolded or opened, in order to hold the end walls flat and thereby prevent the box from collapsing. The strips 60 are secured between the double layers or

thicknesses of the box, and extend across the fold lines, but the strips are exposed between the flaps 17 at the ends of the box, which may not be so desirable as to have the strips completely concealed as shown in 70 Figs. 1, 2 and 3. However, the strips may extend across different fold lines of the box, and may be in different positions or locations.

Figs. 8 and 9 illustrate a box composed of 75 the bottom 14', side walls 15', and end walls 16', with the walls secured together in the same manner as hereinbefore described, and the end walls provided with the fold lines 23' to enable the box to be folded in the same 80 manner. The strips 24'' are shown as being confined within the double corner portions of the box. The side walls 15' have the flaps 25' with the props 26' to seat on the bottom of the box behind the end walls 16', and said end walls have flaps 27 to overlap the flaps 25'. This type of box, without the fold lines 23', is disclosed in said 85 pending application. In order to enable the flaps 27 to fold, they have diagonal fold 90 lines 28 coinciding with the fold lines 23', so that the flaps 27 fold with the end walls 16', as seen in Fig. 9. When the box is folded, the flaps 25' overlap one another, and the props 26' may be flat with the flaps 25' so as to be disposed over the end walls. 95

Having thus described the invention, what is claimed as new is:—

1. A box comprising a bottom, and walls having fold lines to permit the bottom and walls to be folded together, and concealed bendable means permanently secured to the box across a fold line thereof to be bent when the walls are swung relatively to the bottom and composed of material tending to hold its shape in order to hold the box open when unfolded. 100

2. A box comprising a bottom, and walls having fold lines to permit the bottom and walls to be folded together, and concealed bendable strips permanently secured to the box and extending across some of the fold lines to be bent when the walls are swung relatively to the bottom and composed of material tending to maintain its shape so 105 as to hold the box open when unfolded. 110

3. A box comprising a bottom, and walls having double thickness portions and fold lines to permit the bottom and walls to be folded together, and bendable means secured within said double thickness portions and extending across some of the fold lines to be bent when the walls are swung relatively to the bottom and composed of material tending to maintain its shape for holding 120 the box open when unfolded. 125

4. A box comprising a bottom, and walls having double thickness portions and fold lines to permit the bottom and walls to be folded together, and bendable metal strips 130

secured in said double thickness portions and extending across some of the fold lines to be bent when the walls are swung relatively to the bottom and tending to maintain their shape in order to hold the box open when unfolded.

5. A box comprising a bottom and walls, said walls having double thickness corner portions, and having fold lines to permit 10 the bottom and walls to fold together, and bendable means secured in said double thickness portions and extending across some of the fold lines to be bent when the walls are swung relatively to the bottom and composed of material tending to maintain its 15 shape for holding the box open when unfolded.

6. A box comprising a bottom, and walls having flaps secured to the adjacent walls to provide double thickness corner portions, 20 there being fold lines between the bottom and walls and other fold lines between the walls, some of the walls having fold lines to permit the bottom and walls to be folded together, and bendable metal strips secured between 25 some of the walls and said flaps and extending across some of the fold lines to be bent when the walls are swung relatively to the bottom and tending to maintain their shape in order to hold the box open when 30 unfolded.

In testimony whereof I hereunto affix my signature.

SAMUEL KOFF.
